UNITED STATES PATENT OFFICE.

GEORGE M. MARR, OF PHILADELPHIA, PENNSYLVANIA.

DESIGN FOR A PROTECTIVE CAP.

60,356.

Specification for Design.

Patented Feb. 7, 1922.

Application filed January 15, 1921. Serial No. 437,603. Term of patent 7 years.

To all whom it may concern:

Be it known that I, GEORGE M. MARR, a citizen of the United States, residing at 4424 Sanson Street, in the city of Philadelphia, county of Philadelphia, and State of Pennsylvania, have invented a new, original, and ornamental Design for a Protective Cap, of which the following is a specification, reference being had to the accompanying drawing, forming part thereof.

Fig. 1. is a side view of the protective cap.

Fig. 2. is a plan view of the protective cap.

Fig. 3. is a bottom plan view of the protective cap.

I claim:

The ornamental design for a protective cap as shown.

GEORGE M. MARR.
